[57] **CLAIM**

The ornamental design for a resilient template for racking billiard balls, as shown and described.

DESCRIPTION

FIG. 1 is a top plan view of a resilient template for racking billiard balls, showing our new design;

FIG. 2 is a side view thereof, the other unshown sides being of identical appearance;

FIG. 3 is a sectional view thereof taken in the direction of the arrows upon the line 3—3 of FIG. 1; and,

FIG. 4 is a top and side perspective view thereof.
